[57] CLAIM

The ornamental design for a wheel chock, as shown and described.

DESCRIPTION

FIG. 1 is a front perspective view of a wheel chock showing my new design.

FIG. 2 is a top plan view of the wheel chock.

FIG. 3 is a front elevational view of the wheel chock, with the rear elevational view being a mirror image of FIG. 3.

FIG. 4 is a left side elevational view of the wheel chock.

FIG. 5 is a right side elevational view of the wheel chock; and,

FIG. 6 is a bottom plan view of the wheel chock.
